J. E. Smith,
Meat-Cutters.

Nº 74.947.

Patented Feb. 25, 1868

Inventor
John E. Smith

United States Patent Office.

JOHN E. SMITH, OF BUFFALO, NEW YORK.

Letters Patent No. 74,947, dated February 25, 1868.

IMPROVED MEAT-CUTTER.

The Schedule referred to in these Letters Patent and making part of the same.

TO ALL WHOM IT MAY CONCERN:

Be it known that I, JOHN E. SMITH, of Buffalo, in the county of Erie, and in the State of New York, have invented certain new and useful Improvements in Meat-Cutters; and do hereby declare that the following is a full, clear, and exact description of the construction and operation of the same, reference being had to the annexed drawings, making a part of this specification, in which—

Figure 1 is a front elevation.

Figure 2, a vertical section through the frame for holding the knives, the mechanism for adjusting said frame vertically, and the cutting-block and box, also part of the frame below it.

Figure 3 represents a plan or top view of meat-box and knife-frame.

The nature of my invention consists in, first, placing the cutting-mechanism on a central shaft, which passes up through the cutting-block, said shaft receiving its motion from a crank, or other equivalent means, below the block; second, making the knives adjustable, vertically, on said shaft; third, in the employment of a spring for preventing the breaking of the knives by fragments of bones or other obstructions, said spring being so arranged that the knives will yield when an obstruction is placed beneath them; fourth, in the employment of a double eccentric, for giving the necessary movements to the cutting-block.

A, in said drawings, represents the meat-box; B, the cutting-block; C, the vertical shaft or rod, to which is attached the frame holding the knives; D represents said frame; E, the knives, any number of which, from three upwards, may be used. The bolts for holding them on to the frame are marked F. G, in fig. 2, is a ring or collar, made to fit and move easily up or down the shaft C. It may be fastened firmly, at any point on said shaft C, by means of the set-screw H. I is the spring, for allowing a yielding motion to the frame and knives when obstructions of any kind (while the machine is in operation) come in the way. The power of the spring is regulated by the jam-nuts J. As the block is worn away by continued cutting, the cutters and frame may be adjusted to meet it, by means of the collar G, set-screw H, and jam-nuts J. K, in fig. 2, represents a tube, through which the shaft C works. It passes through the centre of the cutting-block, where it is firmly fastened. It acts as a support to said shaft C, and also forms a centre, upon which the cutting-block turns, the lower part of it working in a socket, L, as shown in fig. 2. The lower end of shaft C is kept in place by the brace M, as shown in fig. 2; at N it is made square, as shown, to prevent its turning. O is a connecting-rod, which is jointed to the shaft C at the point Q, and to the crank P at the point R, as shown in said fig. 2. The letters S represent friction-rollers, which act as supports for the cutting-block, and, at the same time, allow it to move easily. T and U, in fig. 1, represent the double eccentric. It is fastened to the shaft Z. To each eccentric is fastened a lever, as shown, and marked U' and T'. The two levers are kept in place or position by a pin, which is firmly fastened to the frame, and passes through a slot in each lever, as shown at V in fig. 1. W and X represent two bars or springs, which are fastened firmly to the levers U' and T', as plainly shown in the drawing. These bars are bent at the ends, to form catches, which, during the operation of the machine, are made, by means of the eccentrics, to catch into the notches Y, and give the necessary motions to the meat-box, which must move two notches for each revolution of the crank A², as shown in fig. 1. The notches Y are made of cast iron, in the form of a ring, which is firmly fastened to the bottom of the cutting-block, as shown. The framework of the machine is also made of cast iron, and the knives or cutters of sheet steel. C², in fig. 1, represents the fly-wheel, D² a spur-wheel, both of which are fastened to the shaft Z. B² is a pinion, which is fastened to the shaft Z², and gears with the wheel D², as shown.

The machine is operated by the crank A, which, as will be readily seen, gives motion to the pinion B², which, in turn, gives motion to the wheel P and connecting-rod O, which, of course, gives the necessary reciprocating motions to the cutter-frame and cutters, while the double eccentric turns the meat-box one notch ahead for every downward motion of the knives or cutters.

What I claim as my invention, and desire to secure by Letters Patent, is—

1. The combination of the central shaft C, the cutting-knives E E, and the spring I, or its equivalent, substantially as and for the purposes herein described and set forth.

2. The double eccentrics T and U, the bars or spring-catches W and X, or the equivalent thereof, and the levers U' and T', when constructed and arranged substantially as and for the purposes described.
